SINGLE-DOSE TUBE

Harold F. Temple, Freeport, N. Y., assignor to
 Victor Metal Products Corporation, Brooklyn,
 N. Y., a corporation of New York

Application August 20, 1938, Serial No. 225,998

7 Claims. (Cl. 220—27)

This invention relates to single dose containers and more particularly to containers incorporating a readily frangible section.

Prior to the instant invention, it has been proposed that containers be provided with frangible areas but such containers have been awkward to puncture requiring special equipment and have been generally found to be unsatisfactory. Other prior containers having frangible areas have been relatively difficult to puncture by reason of their inferior organization.

It has also been proposed that single dose containers be fabricated with a section permitting rupture by the finger-nail but practice has demonstrated that such devices have a tendency to rupture prematurely and therefore are unsatisfactory for general use.

It is an object of the invention to provide a single dose container having a readily frangible section adapted to be easily ruptured by the finger-nail and located in a plane at variance with the exterior surface of the container.

It is a further object of the invention to provide a single dose collapsible tube having a readily frangible area adapted to be ruptured by the fingernail which frangible area is protected against premature rupture.

Other objects and the nature and advantages of the invention will be apparent from the following description taken in conjunction with the accompanying drawing, wherein:

Fig. 1 is an enlarged fragmentary sectional view of the upper portion of the tube.

Fig. 2 is a view similar to Fig. 1, with the frangible section ruptured.

Fig. 3 is a view similar to Fig. 1 but taken at right angles thereto.

Fig. 4 is an elevational view of the entire tube.

Fig. 5 is a top plan view, and

Fig. 6 is a view similar to Fig. 5 with the frangible section ruptured.

Referring to the drawing, a collapsible tube 10 comprising a body portion 11, a frusto conical portion 12, and a teat-like protuberance 13 is formed with a slot 14 in its upper portion. The substantially cylindrical side walls 15 of the teat-like protuberance 13 are formed with a rounded or curved head portion 16 of relatively thick section as compared with the curved frangible wall 17 which forms the lower surface of the slot 14.

The inner faces of the walls 18 which form the side walls of the slot 14 are spaced apart sufficiently to accommodate the fingernail of the user of the tube whereby a flick of the thumbnail across the frangible section 17 in a direction of

the axis of the slot 14, will produce a discharge opening in the tube 10, and upon compression of the body 11 of the tube, the material with which the tube is filled will be ejected from the slit-like opening 19, see Figs. 2 and 6 which illustrate the tube after rupture of the frangible section. 5

With the frangible section 17 having a curved section, as illustrated in Figs. 1 and 3, the same is adapted to be readily sheared by the fingernail 10 and yet sufficient strength is embodied in the structure at the slot 14 whereby premature rupture is prevented. This strength inherent in the structure is due in part to the location of the frangible section 17 in a plane at variance with 15 the external surface of the head portion 16 of the teat-like protuberance 13.

It is to be noted that the frangible section 17 does not extend to the outer circumferential margin 20 of the head portion 16, yet the slot 14 does 20 extend to this margin whereby though the slot may be readily located by the fingernail yet the small edge portions 21 of the frangible section are not weakened as they would be if they extended to the outer margin 20. 25

The structure recited above has been found to be capable of being filled, stored and handled without premature rupture and also is an improvement over prior tubes which had a tendency to develop leaks and otherwise prove unsatisfactory for practical purposes. 30

It will be obvious to those skilled in the art that various changes may be made in my device without departing from the spirit of the invention and therefore I do not limit myself to what 35 is shown in the drawing and described in the specification, but only as indicated by the appended claims.

I claim:

1. A single dose container including a protuberance having a convex curved head portion incorporating a convex curved frangible section located in a plane at variance with the external surface of said head portion. 40

2. A single dose collapsible tube comprising a 45 body portion and a protuberance having a convex curved head portion, a slit-like groove formed in said head portion and extending to substantially its outer margins, the lower wall of said groove comprising a convex frangible section, 50 whereby the frangible section may be ruptured by a flick of the thumb nail guided by the walls of the groove therethrough.

3. A container comprising a body portion and a protuberance having a convex curved head por- 55

tion, said head portion being formed with a transverse groove extending to substantially the upper outer margins of said protuberance, a convex curved frangible section formed in a wall of said groove but being spaced from said outer margins, whereby the frangible section may be ruptured by a flick of the thumb nail guided by the walls of the groove therethrough.

4. A single dose collapsible tube comprising a body portion, a frusto-conical section, a teat-like protuberance comprising a cylindrical portion and a head portion, said head portion being rounded and being formed with a transverse groove in its upper surface extending to the outer margins of said protuberance, the lower portion of said groove being formed with a relatively thin frangible area extending along the axis of said groove but being spaced from the outer margins of same and being curved, whereby the said readily frangible area may be ruptured by a flick of the thumbnail and the unruptured container be of sufficient strength to prevent premature failure.

5. In a single dose collapsible tube, a body portion, a frusto-conical section, a protuberance extending from said frusto-conical section and being axially aligned therewith, said protuberance including a convex curved head portion and formed with a transverse groove, the lower por-

tion of said groove being formed with a relatively thin convex curved frangible area extending along the axis of said groove, whereby the said readily convex curved frangible area may be ruptured by a flick of the thumb nail and the unruptured container be of sufficient strength to prevent premature failure.

6. A collapsible tube comprising a body portion and a protuberance, said protuberance including a head portion, said head portion being formed with a transverse groove, the lower portion of said groove being formed with a relatively thin convex curved frangible area extending along the axis of said groove, whereby the said readily convex curved frangible area may be ruptured by a flick of the thumb nail guided by the walls of the groove therethrough.

7. A single dose collapsible tube comprising a body portion and a protuberance, said protuberance including a head portion formed with a transverse groove, the lower portion of said groove being formed with a relatively frangible area having symmetrical portions sloping outwardly and downwardly in opposite directions and axially of said groove, whereby the readily frangible area may be ruptured by a flick of the thumb nail guided by the walls of the groove therethrough.
